(57) **CLAIM**

The ornamental design for a curing element for a hand-held dental curing tool, as shown and described.

DESCRIPTION

FIG. 1 is a top perspective view of a curing element for a hand-held dental curing tool of the present invention; FIG. 2 is a side view thereof;

FIG. 3 is a top view thereof;

FIG. 4 is a bottom view thereof;

FIG. 5 is a front view thereof; and,

FIG. 6 is a rear view thereof.

The broken lines are included for the purpose of illustrating an environment of the design only and form no part of the claimed design.
